(57) **CLAIM**

The ornamental design for a bottle top identifier, as shown and described.

DESCRIPTION

FIG. 1 is a top-front-left perspective view of a bottle top identifier showing my new design;

FIG. 2 is a bottom-rear-right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof;

FIG. 8 is a left elevational view thereof; and,

FIG. 9 is a cross sectional view taken in the direction of line 9-9 in FIG. 4.

The broken lines showing of indicia in FIGS. 1 and 5 are included for the purpose of illustrating environmental structure and form no part of the claimed design.
